(57) **CLAIM**

The ornamental design of the tool for removing price labels from retail shelf, substantially as shown and described.

DESCRIPTION

FIG. 1 is a top view of a tool for removing price labels from retail shelf showing my new design, the tool is shown withdrawn from its safety cap for clarity of illustration; FIG. 2 is front view thereof, the rear view being a mirror image;

FIG. 3 is a bottom view thereof;

FIG. 4 is a left side view thereof;

FIG. 5 is a right side view thereof;

FIG. 6 is a top view of the tool safety cap thereof, shown separately for clarity of illustration, the bottom view being identical;

FIG. 7 is a front view thereof, the rear view being identical; FIG. 8 is a left side view thereof;

FIG. 9 is a right side view thereof;

FIG. 10 is a top view of the tool for removing price labels from retail shelf;

FIG. 11 is a front view thereof; and,

FIG. 12 is a right side view thereof.
